BREECH BLOCK FOR FIREARMS

Antonio Marcati, Buenos Aires, Argentina, assignor to
Gildo Marcati, Buenos Aires, Argentina

Application May 21, 1951, Serial No. 227,403

3 Claims. (Cl. 42—16)

This invention relates to improvements in automatic or semiautomatic firearms, and has as one of its main objects to provide means resulting in a substantial simplification in the construction of the breech mechanism together with the firing-pin and the recoil spring.

In automatic or semiautomatic firearms in which the reaction of the cartridge case results in the displacement of the breech block, which has to overcome the resistance opposed by the mainspring so as to return the block to its original or starting position, the design of said block and its actuating pieces, such as the firing-pin and the recoil spring, becomes very important. The wear of the material must be kept to a minimum and undesirable working stresses are to be eliminated, which appear when the different parts operate under unusual working conditions.

The fundamental features which should be taken into consideration for the construction of the breech block and its accessories are: the general dimensions of the assembly should be reduced to a minimum consistent with the mass required so that the inertia of the moving pieces delays the opening of the combustion chamber until the bullet has left the barrel; and the assembly and disassembly of the breech block should be as simple as possible.

The first of these features greatly affects the weight of the firearm on permitting the reduction of the dimensions of the housing in which the breech block runs. In this sense the limit has been practically attained, by making the recoil spring reach the breech block farther than the back of the hammer. For this purpose the recoil spring is arranged almost on the surface of the breech block, the hammer being in an oblique position relative to the block axis. The foregoing arrangement used in some of the fire arms known up to the present, has the disadvantage, since the recoil spring is eccentrically operated, of needing a perfect adjustment between the block and the case, if the uneven wear originated by the eccentric impulse is to be reduced to a minimum; moreover, the hammer working in an oblique way is subject to considerable transverse stresses which rapidly bring about weakening and weariness of the material.

With respect to the assembly characteristics, the problem is directed almost solely to the recoil spring because the latter presents most of the difficulties for its mounting since it should be installed in most cases in compressed state which means a risk for the operator if he does not have adequate tools available. Recently, a good solution has been found by employing a telescopic capsule that houses the recoil spring, but the manufacture of same is rather complicated and results in high production costs.

It is an object of the present invention to provide a new arrangement of the recoil spring with respect to the firing-pin, all within the bolt, or the breech block, which allows the firing-pin to be mounted parallel to the block axis.

A feature of this invention resides in the fact that the

recoil spring is totally confined in the breech block, surrounds the firing-pin, and bears with one end against a rod, slideable in a bore of the block. The other end of the rod rests against a portion of the housing or chamber of the breech block. The axis of the spring, the rod and the breech block and the firing-pin may be the same.

Another feature of this invention is that the rod, against which one end of the recoil spring bears, has at its front end an interlocking projection, or other means which cooperates with a stop or projection arranged in the rear part of the firing-pin, so that release of the spring, and said rod, is prevented, and the bolt or breech block may be disassembled from the firearm as a unit without manipulating the spring.

Still a further feature of this new device is constituted by the provision of means to limit the travel of the firing-pin with respect to the breech block. This limiting means acts as a stopping means for the recoil spring, keeping it assembled within the breech block and to the firing-pin and the spring rod, thereby facilitating field-stripping and clearing of the firearm.

The invention will now be described in greater details in the following description of one of its preferred forms of construction, which has been illustrated in the attached drawing and in which:

Fig. 1 shows a longitudinal section of a breech block for an automatic or semiautomatic carbine, constructed in accordance with the present invention.

Fig. 2 illustrates a transverse section of said breech block taken along lines 2—2 of Fig. 1.

Fig. 3 shows a similar section taken along lines 3—3 of Fig. 1.

Referring now to the drawing, and particularly to Fig. 1, there is shown a bolt or breech block 1 of generally cylindrical shape which is disposed in a housing or chamber 2, (partly represented in dotted lines) and in which said block may freely move. The chamber is closed at one end by a removable back cover 2a. The bolt 1 is provided on its front face 5 with an extractor 3, which engages the rim of a cartridge in the usual manner during the recoil of the block. An ejector (not shown) may also be provided in a conventional manner. In its lower part, the breech block 1 is provided with a series of recesses 4, which allow the front face 5 of block 1 to pick up and push a new cartridge from a magazine into firing position. The breech block 1 is hollow, as shown, having a longitudinally extending bore 6 terminating at its front end in a perforation 7 of lesser diameter to thereby form a shoulder in said bore 6; the shoulder in bore 6 thus constitutes a seating surface 8 on which one end of a recoil spring 9 is supported; spring 9 surrounds the pin 10 acting as guide means for the firing-pin. The firing-pin 10 is entirely enclosed in the breech block and ends in its rear part in a bifurcated jaw 11 which projects beyond spring 9 to slide in a slot 12 in the block 1; in the mouth 13, formed by the bifurcated jaw 11, a holding pin 14 is loosely disposed in a transversely extending slot 15. The pin 14 has its ends formed with the same curvature as the bolt 1 (Fig. 2); pin 14 will therefore be retained in the bolt 1 by the wall of the chamber 2 as can be visualized from Fig. 2. The pin 14 acts as a stop for the stroke of firing pin 10, the jaw 11 being normally pressed toward it by the spring 16 urged against finger or prong 17, which bears against the outside face 65 of jaw 11, as shown in Fig. 1.

The firing-pin 10 is preferably of square cross-section and passes through an eye 18a of equal cross-section made in the front end of a grooved rod 18, this rod 18 serving as a means of support or abutment for the opposite end of the spring 9. Rod 18 is formed with a groove 19 as a guide for the firing-pin 10. The external contour of the rod 18, in this case of circular shape, is formed

to match the bore 6 into which (during the recoiling travel of the block 1) the rod 18 extends. A recess 20 made in the lower end of the rod 18 allows the hammer 21 to reach the jaw 11 of the firing-pin 10 at a convenient height.

The assembly is provided with a handle 22 which is disposed transversely of the block 1 and received therein (see Fig. 3). The inner part of handle 22 is formed with a recess having the same form as the wall of the bore 6; externally of the block 1 the handle has a notch 24 running in a longitudinal groove of the wall of the chamber 2; this handle permits manual, external operation of the breech block.

The operation of the various pieces mounted on the breech block is restricted to the inward movement of the firing-pin 10 when the hammer 21 strikes the back of the jaw 11 to thereby overcome the tension of spring 16 in such a way that the tip of the firing-pin 10, protruding beyond spring 9 and the front of the block 1, strikes the cartridge case. The explosion of the cartridge causes recoil movement of the block 1 against tension of spring 9, and further penetration of the rod 18 into the bore 6, the firing-pin 10 sliding in the groove 19. This recoil movement also causes the compression of the spring 9 between the seat 8 and the front end of the rod 18 as well as the rotation of the hammer 21 to the firing position. The energy accumulated in the spring 9 pushes the block 1 inward which results in feeding the chamber with a new cartridge, thus the block being ready to fire again.

To disassemble the mechanism, the back cover 2a of the chamber 2 is removed which permits a little expansion of the spring 9 until the rod 18 is stopped in front of the jaw 11; jaw 11 is held in the breech block 1 by the pin 14 which also prevents the firing-pin 10 from running out backwards. In this condition the assembly is locked together and can be withdrawn from the rear of chamber 2 as a unit, without the risk of having the spring 9 shoot off. Once the breech block is removed from chamber 2, the pin 14 can be removed from its seat in slot 15, thus freeing the jaw 11 and permitting the withdrawal of the firing-pin 10 and the easy disassembly of all the pieces. For the assembly one proceeds in a reverse order.

It should be understood that the description, as well as the attached drawing are set out only as a demonstrative form and not limitative, it being permitted to introduce any kind of modifications in appearance, construction and detail not exceeding the scope of the invention such as defined in the following claims.

I claim:

1. In a firearm; a breech housing, an elongated breech

50

block slidably mounted lengthwise of and relative to said housing, said breech block having at one end thereof a front face adapted to bear against a cartridge and a rear portion at the other end thereof, said breech block having a bore extending from said rear portion of said breech block in substantially longitudinal direction of the latter toward said front face and terminating short thereof, said front face having a relatively small aperture coaxial with said bore and communicating with the latter, a firing-pin disposed in said breech block and movable in said bore, said firing-pin having a rearward portion and a forward portion, an elongated recoil spring completely seated within said bore and guidingly surrounding the major portion of said firing-pin, said forward portion of said firing-pin extending beyond said recoil spring into said aperture and being adapted to strike against a cartridge, an elongated rod having a forward end and slidably mounted in said bore relative to said firing-pin and bearing against an end of said recoil spring, said forward end of said rod encircling said rearward portion of said firing-pin adjacent said spring, said rearward portion of said firing-pin including an enlarged end, said forward end of said rod including means interlocking with said enlarged end of said firing-pin, and means operatively associated with said breech block and disposed in the path of sliding movement of said firing-pin between said forward end of said rod and adjacent said enlarged end of said firing-pin to prevent disassembly of rod and breech block.

2. A firearm according to claim 1, wherein said operatively associated means includes a holding pin removably mounted in the breech block and extending substantially in transverse direction to and below the axis of said firing pin, said enlarged end of said firing-pin including a bifurcated jaw for receiving said holding pin.

3. In the firearm according to claim 1, wherein said forward end of said elongated rod includes an eye operatively receiving the firing-pin forwardly of the enlarged end thereof.
